UNITED STATES PATENT OFFICE.

JOHN S. ADAMS, OF ELGIN, ILLINOIS.

WINDMILL.

SPECIFICATION forming part of Letters Patent No. 233,178, dated October 12, 1880.

Application filed April 5, 1880. (Model.)

To all whom it may concern:

Be it known that I, JNO. S. ADAMS, of Elgin, in the county of Kane and State of Illinois, have invented certain new and useful Improvements in Windmills; and I do hereby declare that the following is a full, clear, and exact description thereof, reference being had to the accompanying drawings, making a part of this specification, in which—

10 Figure 1 is a side elevation of my mill with the wheel thrown into the wind. Fig. 2 is a like view of the same with said wheel thrown out of the wind. Fig. 3 is a plan view of the upper side of said mill, the full lines showing the relative positions of parts when the wheel is thrown into the wind and the dotted lines the positions of parts when said wheel is thrown out of the wind. Fig. 4 is an enlarged side elevation of the bearings of the wind-wheel and vertical shaft and the gearing employed for communicating motion from the former to the latter. Fig. 5 is a vertical section of the same upon a line passing through the longitudinal centers of the bearings. Fig. 25 6 is a side elevation of the turn-table. Fig. 7 is a vertical central section of the same. Fig. 8 is a perspective view of one of the couplings employed for connecting together the rim-sections. Fig. 9 is a central longitudinal section 30 of the same. Fig. 10 is a perspective view of one of the couplings used for connecting together the inner rim and spokes. Figs. 11 and 12 are respectively a perspective view and a longitudinal section of one of the connections employed for securing together the radial arms and outer rim. Fig. 13 is a perspective view of one of the clips employed for connecting the sails with the rims, and Fig. 14 is a central longitudinal section of the same 35 when applied to use.

Letters of like name and kind refer to like parts in each of the figures.

The design of my invention is to increase the strength of a windmill and to render practically automatic its operation under variations in the velocity of the wind; to which end it consists, principally, in the construction of the wind-wheel frame and the combination of the parts composing the same, substantially as and for the purpose hereinafter specified.

It consists, further, in the means employed

for connecting together the rim-sections and spokes of the wheel-frame, substantially as and for the purpose hereinafter shown.

It consists, further, in the means employed 55 for connecting together the rim-sections and sails, substantially as and for the purpose hereinafter set forth.

It consists, further, in the means employed for lubricating the bearing of the windmill, 60 substantially as hereinafter specified.

It consists, further, in the construction of the bearing of the gear of the vertical shaft and the means employed for lubricating the same, substantially as and for the purpose hereinaf- 65 ter shown.

It consists, further, in the means employed for automatically regulating the velocity of the wind-wheel with relation to the force of the wind, substantially as hereinbefore set 70 forth.

It consists, further, in the means employed for throwing the wind-wheel into or out of the wind, substantially as and for the purpose hereinafter shown and described.

It consists, further, in the construction of the turn-table, substantially as and for the purpose hereinafter specified.

In the annexed drawings, A represents a platform, which is preferably supported upon 80 three rods or tubes, B, which are suitably attached to its lower side, and from thence extend downward and outward, and have their lower ends properly anchored.

From the platform A a tube, C, extends upward to a suitable height, and at its upper end has a peripheral enlargement, c, within the upper end of which is formed an annular groove, c', while within the outer surface of said enlargement is provided a circumferential 90 groove, c'', as shown in Fig. 7.

Fitted loosely within the tube or standard C is a tube, D, which extends from the lower end of the same upward to a height which is governed by the dimensions of the windmill, 95 and at a point corresponding to the upper end of said standard has secured a collar, d, that embraces the upper end and outer side of the enlargements c, and is provided with a tongue, d', which projects downward into the 100 groove c''. Two set-screws, d'', pass radially inward through the sides of said collar, and

have their inner ends contained within the peripheral groove f^2 of said enlargement, in which position said screws prevent vertical movement of said collar without interference with its freedom of rotary movement.

5 The construction described furnishes a turn-table bearing for and upon which the side pressure of the windmill is supported and freedom of rotary motion of the same secured.

10 Secured to or upon the upper end of the tube D is a casting, E, which in side elevation has the form of a Greek cross, as shown in Fig. 4.

Within the end of one of the horizontal arms of said part E is secured one end of a pin, F, 15 which in shape corresponds to the shape of an ordinary axle-arm, and upon its outer end is provided with a screw-cap, G.

Upon the pin or bearing F is fitted a sleeve or box, H, which at its inner end is provided 20 with a bevel-gear, I, that preferably forms part of said box. As said box forms the hub or center of my wind-wheel, the following-described means are provided for securing a proper lubrication of the same.

25 Within the upper side of the arm F is formed a longitudinal groove, f, which extends nearly to each end, and at its ends connects with two vertical openings, f', that pass downward to and connect with an axial opening, f², which

30 passes from the outer end of said arm or bearing nearly to the inner end of the same. An opening, f³, extends from the axial opening f², at the longitudinal center of the arm F, downward to the lower side of said arm, where it

35 opens into a chamber, h, which is formed by recessing out the hub H. An oil-cup, K, passing radially through said hub, with its inner end in communication with said chamber h and its outer end covered by a cap, k, and a

40 screw-plug, f⁴, fitted into the outer end of the axial opening f², completes the lubricating construction, the operation of which is as follows, viz: The groove f is now filled with lamp-wick, or other like fibrous absorbent material,

45 a quantity of oil poured into and through the cup K until the chamber h is filled, when the cap k is screwed on. If, now, the hub H is caused to rotate, the cup K receives a quantity of oil each time it passes downward, which oil

50 is discharged upon the wicking as said cup passes over the same. A portion of the oil discharged upon the wicking is transferred directly to the bearing-surfaces, and another portion passes through the openings f' into the

55 central cavity, f², from whence it escapes through the opening f³ into the chamber h, such circulation being constant, and each portion of the bearings thoroughly lubricated.

From the hub H, at the front side of the gear

60 I, a number of hollow tubular arms or spokes L—preferably eight—extend radially outward from equidistant points, and are secured in relative positions by means of U-shaped straps l, one of which passes over each arm and 65 through said gear, and has upon its threaded ends, that project through the rear side of the

latter, nuts l', by which said straps may be caused to draw said arm firmly against the front face of said gear.

If desired, the arms L may be secured in place by threading exteriorly their inner ends and screwing the same into threaded holes in the hub H. From the outer end of the hub H a second series of arms, L', extend radially outward and rearward, and have their outer ends 75 in close proximity to the outer ends of the arms L.

The outer ends of the radial arms L and L' are connected together circumferentially by means of a tubular rim, M, which has a circular form, and is composed of sections which correspond in number to the number of said spokes and in length to the distance between the ends of the same.

80 The sections of the rim M and the radial arms L and L' are secured together by means of connections N, which have the form shown in Figs. 11 and 12, and are each provided with two radial converging threaded openings, n, for the reception of the threaded outer ends of 90 said arms, and a cross-opening, n', for the reception of one of said rim-sections. A set-screw, n², passing radially inward through the outer end of said connection, impinges upon said rim-section M and confines the latter 95 firmly in place.

100 The rim-sections are connected together between the arms L by means of clamps O, which are composed of two plates that are constructed to embrace one end each of two sections, and a bolt, o, which passes through the centers of said plates between said section ends, as shown in Figs. 8 and 9. These clamps are easily applied in or removed from position, and when in place firmly connect together the rim-sections 105 and render the same practically continuous.

110 Midway between the outer rim, M, and the hub H is a second rim, M', which, like that before named, is constructed in sections from tubing, and has the ends of its sections connected together by clamps O. As said inner section is placed against the outer sides of the radial arms L, a different form of coupling is required from that employed in connecting said outer rim and spokes.

115 The coupling N' has the form of two short tubes cast together, one of which receives the spoke or arm L and the other one of the curved sections M. A set-screw, n', passing laterally inward from the rear side of said coupling, 120 impinges upon said arm L and insures the relative positions of parts.

The rims M serve as supports for a series of vanes or sails, P, each of which latter is connected to both of the former by means of two 125 clips, Q, (seen in Fig. 11,) which clips consist of a thimble that embraces the rim and secured thereon by a set-screw, q, and a plate that extends to the sail and is secured upon the sail by means of a screw, q', passing through 130 said parts, as shown in Fig. 12.

By the use of the clips described the sails may

be securely attached at any desired angle with relation to the plane of the wheel, and when in place offer but slight opposition to the passage of air between said sails.

5 The motion of the wind-wheel is communicated through the gear-wheel I to a similar gear-wheel, R, which is secured upon the upper end of a shaft, S, that is journaled within and extends downward through the casting E 10 and tubes C and D. The weight of the shaft S is supported by the gear-wheel R, which latter, as seen in Fig. 5, is provided upon its lower face, near its center, with a downward-projecting annular flange, r, and rests upon a 15 cap, T, that has a groove, t, which corresponds to and receives said flange, the upper face of said cap and the lower face of said gear furnishing the necessary bearing for the latter and said shaft, while said groove t holds oil for 20 lubricating said bearing, which oil is conveyed to the bearing parts by means of said flange r. Oil for said bearing may be supplied through an opening provided in and through said gear and communicating with said groove.

25 In order that the shaft S may be prevented from vertical displacement, a collar, s, is formed upon said shaft just below the cap T, and bears against the lower side of the latter, being contained within a recess, e, that is provided in 30 the casing E. Hinged to or upon the rear end of the casing E is a tail-vane, U, which consists of a horizontal bar, u, which decreases regularly in thickness from its front to its rear end, a thin metal or wooden plate, u', placed 35 edgewise and centrally within said bar, and a rod or rods, u², extending from near the longitudinal center of said bar forward and upward to a rectangular open frame, u³, which forms the front end or hinged portion of said vane.

40 The vane U is hinged upon the casting E, so as to swing horizontally for the purpose of varying the position of the windmill with relation to the direction of the wind, such movement being limited to a little more than one-fourth of a revolution by means of two rods, e' and e², the first of which extends in a line with the arm F rearward from said casting, and then laterally toward a buffer, u⁴, which is 45 attached to the frame u³, while said rod e² extends from the opposite side of said casting laterally outward, and thence rearward, and 50 engages with said buffer u⁴ whenever said vane has reached the limit of its motion in such direction.

55 As thus connected with the wind-wheel, it will be seen that, if the vane U is turned to one side out of line with the course of the wind, the force of the latter will bring said vane into line again and cause the face of 60 said wind-wheel to be moved from a position having a right angle to the course of the wind toward or to a position in a line with such course.

In order that the movement described may 65 be automatically produced by the varying force of the wind, so as to cause the wind-

wheel to maintain a uniform speed, the following - described mechanism is employed, viz: Journaled horizontally and laterally within a bearing at the upper rear corner of the frame 70 u³ is a shaft, v, to one end of which is attached a storm-vane, V, which extends downward to the position shown in Fig. 1, when the wind-wheel is in opposition to the course of the wind. To the opposite end of the shaft v is 75 attached an arm, v', which extends downward and slightly forward, and has pivoted to its lower end one end of a bar, W, which from thence extends horizontally forward to and is pivoted upon a stud, w, that extends laterally 80 outward from the casting E. A second arm, v², extends from the shaft v rearward and slightly downward, and upon its rear end has secured a weight, v³. As thus arranged, whenever the force of the wind upon the 85 storm-vane V exceeds the downward pressure exerted by the weight v³ the lower end of said vane will move rearward and upward, and, through the shaft v, arm v', and bar W, will draw the windmill and tail-vane toward 90 the relative positions shown in Fig. 2, and by the dotted lines of Fig. 3, until, if the strength of the wind is sufficient, said parts will be in a line with each other and said wind-wheel nearly or quite out of the wind. 95 As the force of the wind lessens the weight v³ will overcome the resistance offered to the storm-vane V and will force the latter toward or to its normal position, and in the same degree cause the wind-wheel to turn into the 100 wind.

In order that the wind-wheel may be partly or entirely thrown out of the wind for the purpose of adjusting it to any desired speed or of entirely arresting its motion, I place 105 within the tube D, around the shaft S, a tube, X, which extends from near the casting E downward below the platform A, and from its upper end extends an arm, x, rearward through a vertical slot, d³, in said tube D. 110

From the end of the shaft v to which is attached the storm-vane V an arm, v⁵, extends forward and upward, and from its outer end a chain or cord, Y, extends downward to and is connected with the rear end of the arm x, said 115 chain having such length as to be nearly taut when said storm-vane occupies its normal position and the tube X is at its highest point.

Upon the lower end of the tube X is journaled a collar, x', which is engaged by a lever, 120 Z, that is provided with an opening at its center that contains said collar, and has at each side a set-screw, z, that passes through the same and has its inner end contained within a corresponding opening in said collar. One 125 end of said lever is connected by a double hinge-joint to a suitable support, while its opposite end is free to be raised or depressed at will.

When the lever Z is raised to its highest 130 point the movements of the wind-wheel are not interfered with; but when said lever is de-

pressed to its lower limit said wind-wheel is turned out of the wind, and will not be revolved by the latter.

When the lever Z is moved to and secured 5 in position at any point between its extremes the wind-wheel will be correspondingly thrown out of the wind and the effective force of the latter varied in a like degree.

The governing mechanism described enables 10 the speed of the wind-wheel to be adjusted and to be maintained at a uniform rate whenever there is sufficient wind to give the minimum power needed.

Having thus fully set forth the nature and 15 merits of my invention, what I claim as new is—

1. The wind-wheel frame composed of the hub H and gear I, the spokes L, the straps l, the rim-sections M and M', connected together 20 by means of the clamps O and bolts o, and the connections N n and N' n', said parts being combined in the manner and for the purpose substantially as specified.

2. As a means for securing together the 25 outer rim, M, with the spoke L, and in combination therewith, the connection N, having radial and transverse openings and provided with the set-screw n, substantially as shown.

3. As a means for securing together the 30 spokes L and the inner rim, M', and in combination therewith, the connection N' and set-screw n', substantially as set forth.

4. As a means for connecting the sails P with the rims M and M', and in combination 35 with the same, the clips Q and set-screws q, constructed and operating substantially as shown and specified.

5. As a means for lubricating the bearing H of the wind-wheel, the longitudinal groove f, 40 the axial opening f², and the vertical openings f' and f³, formed within the arm F, in combination with the chamber h, provided within the hub H, substantially as shown.

6. The bearing for the shaft S, consisting of the gear-wheel R, provided upon its lower face 45 with the annular flange r, and the cap T, arranged to receive the lower face of said gear-wheel, and having a groove, t, for the reception of said flange, said parts being combined to operate substantially as and for the purpose set forth.

7. In combination with the frame-casting E, the hinged tail-vane U, the shaft r, having attached thereto the storm-vane V and the arms r' and r², the bar W, and stud w, said parts 55 being arranged to operate in the manner and for the purpose shown and described.

8. In combination with the storm-vane V and its connecting mechanism, the tube X, arranged to move vertically within the tube D, 60 and provided with an arm, x, that extends rearward from its upper end, and is connected by means of the chain Y with the arm r⁵ of the shaft r, and the lever Z, connected with the lower end of said tube X and arranged to 65 move the same longitudinally, substantially as and for the purpose specified.

9. As a means for journaling the windmill and permitting the same to revolve upon or around a vertical axis, the tube C, provided 70 at its upper end with an enlargement, e, which has an annular groove, e', in its upper end, and a circumferential groove, e², in its periphery, in combination with the tube D, provided with the collar d, that has an annular 75 tongue, d', and set-screws d², said parts being combined to operate in the manner substantially as shown.

In testimony that I claim the foregoing I have hereunto set my hand this 9th day of 80 February, 1880.

JOHN S. ADAMS.
